UNITED STATES PATENT OFFICE.

IRWIN CHASE, OF BAYONNE, NEW JERSEY, ASSIGNOR TO THE ELCO COMPANY, OF BAYONNE, NEW JERSEY, A CORPORATION OF NEW JERSEY.

PLEASURE-BOAT.

1,250,560.

Specification of Letters Patent. Patented Dec. 18, 1917.

Application filed March 13, 1915. Serial No. 14,144.

To all whom it may concern:

Be it known that I, IRWIN CHASE, a citizen of the United States, residing at Bayonne, county of Hudson, State of New Jersey, have invented certain new and useful Improvements in Pleasure-Boats; and I do hereby declare the following to be a full, clear, and exact description of the invention, such as will enable others skilled in the art 10 to which it appertains to make and use the same.

The present invention relates to pleasure boats or cruisers having a length of about 32 feet.

15 It is an object of the present invention to provide a boat of about this length having a cabin forward, a cock pit amidships, with storage space beneath, and an engine room aft adapted to serve as a sleeping cabin. 20 To attain this object I have put the engine farther aft than has heretofore been considered feasible in boats of this type, and I have avoided an abnormal inclination of the propeller shaft by shaping the dead wood in 25 an unusual way and placing the propeller unusually near the surface of the water with the rudder suspended astern on suitable supports. To a certain extent I rely on the following wave to keep the propeller adequately submerged, but even in a following sea this boat has proved free from racing and altogether seaworthy.

30 By thus putting the engine well aft, the forward cabin and cock pit can be of relatively large dimensions, and except for the steering wheel and reverse mechanism in the cock pit, are free from machinery and are clean and convenient.

The particular embodiment of my invention 40 shown in the accompanying drawings provides sleeping accommodations for six persons within the cabins, four in the forward cabin and two in the engine room, and if desired, three more may sleep in the cock pit under a suitable canvas awning with side curtains.

45 The boat has adequate free board, the gasolene supply tanks are located above the water line, and in case of leakage, will 50 empty through the scuppers, draining the water-tight floor of the cock pit. The boat is provided with many accessories and conveniences which will be made clear by the following detailed description, which is to

be taken in conjunction with the accompanying drawings, wherein

55 Figure 1 is an elevation, with the boat stripped of its awning and flag poles;

Fig. 2 is a plan of the same;

Fig. 3 is a sectional elevation through the 60 forward cabin;

Fig. 4 is a sectional plan of the same;

Fig. 5 is a sectional elevation through the 65 cock-pit and engine room;

Fig. 6 is a plan of the cock pit with a 70 sectional plan of the engine room.

Fig. 7 is a transverse sectional elevation on the line 7—7 (Fig. 4) looking forward;

Fig. 8 is a transverse section on the line 75 8—8 (Fig. 4) looking forward;

Fig. 9 is a transverse section on the line 9—9 (Fig. 6) looking forward;

Fig. 10 is a fragmentary transverse section on the line 10—10 (Fig. 6) looking aft;

Fig. 11 is a fragmentary section through 85 the cock pit on the line 11—11 (Fig. 6) looking aft.

In the embodiment shown in the drawings, there is a cabin 2, forward, with steps 3 leading to a cock pit 4 amidships, from 90 which the engine is controlled. Aft of the cock pit is an engine room 5 which can also be used for sleeping quarters, and the engine 6 is positioned partly in this engine room and partly under the transverse seat 7 of 95 the cock pit.

With this general arrangement, the boat is well balanced when built in lengths of 32 feet, or a few feet more or less, and the great convenience in the arrangement is obtained 100 without sacrifice to the efficiency of the engine or the effectiveness of the propeller.

Considering more in detail the particular embodiment shown in the drawings, it will be seen that the forward deck 8 (Fig. 2) is 105 unobstructed and can be reached easily over the side decks 9 and 10 which extend back along side the cabin trunk 11 which is disposed over cabin 2 and has a crowned roof to give adequate head room therein. Suitable port holes 12 and windows 13 give good ventilation and plenty of light in the cabin. Along the sides of this cabin and at the front, are seats 14, 15 and 16 with lockers beneath, the side seats 14 and 15 being 110 adapted to serve at night as berths. The backs of these side seats are each in two sections 17 and 18, the former being stationary

and the latter being mounted on hinges and adapted to swing up as indicated in Fig. 7 for suspension by ropes 19 to serve as upper berths. The hinges are so constructed as 5 to permit the berth to swing out from under the side deck after it is up in horizontal position. By allowing the stationary part 17 of the back to remain in place, there is good 10 head room over that end of the lower berth and good ventilation for the lower berth.

Forward of the cabin berths are alcoves 20 and 21, and a locker 22, through which the bit 23 passes; and forward of the bit is a bulk head against which the fresh water 15 tank 24 is mounted, this tank being accessible through a suitable deck plate.

Immediately aft of cabin 2 is a lavatory 25 with wash bowl and water closet, the wash bowl being supplied by gravity from the 20 fresh water tank 24 in the bow. On the opposite side of the boat is a dresser having room for an alcohol stove 26 and having beneath, under a removable cover 27, a storage space 28 (Fig. 8) for ice, with a cold chamber 29 beneath for provisions. Steps 3 lead 25 up to the floor 30 of the cock pit, but these steps are removable to give access to the space 31 (Fig. 9) under that floor, in which space steamer trunks, boxes, provisions and supplies may be stored. The floor of the 30 cock pit is above water level and is water-tight. It is really a deck and any water taken in over the sides of the boat will drain out through the scuppers 56 so that the cock 35 pit is self-bailing. In addition to this safeguard, the gasoline tanks 32 and 33 are arranged on the cock pit floor under the side 40 seats 34 and 35, and in case of leakage, the gasoline will flow out through the scuppers 56 and will not reach the engine room.

The cock pit combing 36 is bent inward to meet the forward deck house, giving easy access to the side decks, and hand rails 37 (Fig. 1) along the cabin trunk add to the 45 security of persons walking to the forward deck. At night, the three seats around the cock pit can be used as berths if required, a suitable canvas awning being provided.

The boat is steered from the cock pit by 50 means of a steering wheel 38 operating a steel cable suitably attached to the tiller, and a reverse lever 39 in the cock pit operates a link 40 (Fig. 5) to control the reversing lever 41 of the engine. The throttle 55 and spark control 38' may be conveniently located near the wheel. A starting crank 42 in the cock pit actuates a sprocket 43, having chain connection with an overrunning sprocket 43' on the engine shaft so 60 that the engine may be started from the cock pit.

The front end of the engine 6 projects forward under the transverse seat 7 of the cock pit, and this seat is hinged, as indicated in dotted lines (Fig. 5) to give access 65

to the engine for inspection or oiling. The combined engine room and rear cabin 5 has a raised hatch 44 with a sliding top 45 and a ladder 46 leading down from the cock pit. Seats 47 and 48 extend along the sides of 70 the cabin and have lockers beneath them for bedding, clothes and tools, and at night the seats can be used as berths, and on either side of the engine, under corners of the cock pit seats, are lockers accessible from 75 the engine room.

The arrangement of the engine so near the stern of the boat is in many respects unusual, for in most boats of this type, the dead wood stops at about the point marked 80 49 (Fig. 5) and the propeller is located adjacent to that point, and the engine must, therefore, be located well forward in order that its shaft may not have an inefficient declination. As shown in Fig. 5, I have 85 extended the dead wood almost to the stern of the boat, giving it an upward trend between the points 49 and 50. This brings the propeller 51 close to the surface of the water, much closer than has been customary 90 in boats of the overall dimensions here contemplated, and furthermore, necessitates a rudder axis astern of the transom 52 where it is supported on out-board bearings 53 and 54 with its tiller 55 extending into the rear 95 cabin for attachment to the tiller cables controlled by the steering wheel 38. In an emergency, the tiller can be operated by hand from the engine room. With this arrangement the rudder blade may be of the 100 balanced type.

Even with the propeller 51 almost cutting the surface of the water when the boat is stationary, I find that when the boat is in motion, the following wave covers it as much 105 as is necessary for an efficient thrust, and even in a heavy following sea, the propeller stays well covered and the engine does not race through lack of load.

In the drawings, the hull of the boat has 110 been shown as of a cross section which, in my opinion, is best suited for boats of this type, but I am aware that variations may be made in the dimensions and curvature of the hull without departing from the 115 spirit of my invention as defined by the appended claims.

I claim:

1. In a boat of the type described, the combination of a forward cabin, a cock pit 120 amidships and an engine room aft with an extension under a portion of said cock pit, an engine mounted in said engine room with a part thereof in said extension, fuel supply tanks in said cock pit, connections between 125 the engine and the tanks, controlling means for said engine, mounted in said cock pit, and drain passages leading from said cock pit to the outside of said boat; substantially as described.

2. In a boat of the type described, the combination of a forward cabin, a cock pit amidships and an engine room aft with an extension under a portion of said cock pit and forming a seat therein, an engine mounted partly in the main portion of said engine room and partly in said extension thereof, a ladder leading from said cock pit to said engine room adjacent said engine, fuel supply tanks in said cock pit, connection between said engine and said tanks, controlling means for said engine mounted in said cock pit adjacent said seat and drain passages leading from said cock pit to the outside of the boat; substantially as described.

3. In a boat of the class described, having a cabin forward and a combined engine room and cabin aft, the combination of a cock pit amidships having a floor above water level, seats around said cock pit, and an engine in said engine room projecting under one of said seats, said seat being hinged to give access to said engine from said cock pit.

4. In a boat of the class described, a cabin forward, a combined engine room and cabin aft and a cock pit amidships having a floor above the water level, seats around said cock pit, an engine in said engine room projecting under one of said seats, said seat being hinged to give access to said engine from said cock pit, a fuel supply tank in said cock pit under one of said seats and means leading from said cock pit to the outside of said boat to drain said cock pit; substantially as described.

5. In a boat having a length of about 32 feet, the combination of a cabin forward, a combined engine room and cabin aft and a cock pit amidships having side seats and a transverse seat, of an engine in said engine room extending forward under the transverse seat of said cock pit, said seat being hinged to give access to said engine from said cock pit, the floor of said cock pit being above water level, a gasoline tank under one of the side seats of said cock pit above the floor thereof, and means for starting and controlling said engine from said cock pit, and means for steering said boat from said cock pit.

6. A boat of the class described compris-

ing, in combination, a hull, an engine mounted in the aft part of said hull, dead wood extending to the stern of the boat and formed with an upward trend from a point below said engine, a propeller mounted at the rear end of the dead wood and so related to said hull as to be normally near the surface of the water and a shaft connecting said propeller and said engine.

7. A boat of the class described, comprising in combination a hull, a forward cabin, a cock pit amidships, an engine room aft, an engine in said engine room, dead wood extending to the stern of the boat and formed with an upward trend from a point beneath the forward end of said engine room, a propeller mounted at the rear end of the dead wood and so related to said hull as to be normally near the surface of the water, a shaft connecting said propeller and said engine, a transom at the stern of the boat extending over the propeller and a rudder mounted upon said transom; substantially as described.

8. In a cruiser of the type described, the combination of a cabin forward, a cock pit amidships with storage space under the floor thereof accessible from said cabin, an engine room aft, a hinged transverse seat in said cock pit, an engine in said engine room projecting under said transverse seat and accessible from the cock pit, a raised hatch over said engine room, berths along the sides of said engine room, and means giving egress to said engine room over said transverse seat from said cock pit.

9. A boat of the class described, comprising, in combination, a hull, an engine mounted in the aft part of said hull, dead wood extending to the stern of the boat and formed with an upward trend from a point below said engine, a propeller mounted at the rear end of the dead wood and so related to said hull as to be normally near the surface of the water, a shaft connecting said propeller and said engine, a support at the stern of the boat extending over the propeller and a rudder mounted upon said support.

In testimony whereof I affix my signature.

IRWIN CHASE.
